(57) **CLAIM**

The ornamental design for a warehouse robot as shown and described.

DESCRIPTION

FIG. 1 is a first perspective view of a warehousing robot;
 FIG. 2 is a second perspective view thereof;
 FIG. 3 is a rear view thereof;
 FIG. 4 is a front view thereof;
 FIG. 5 is a left view thereof;
 FIG. 6 is a right view thereof; and,
 FIG. 7 is a top view thereof.
